ADJUSTABLE FLOAT MECHANISM FOR
BOTTLE FILLERS

James Kantor, Chicago, Ill., assignor to The Liquid Carbonic Corporation, Chicago, Ill., a corporation of Delaware

Application March 25, 1932, Serial No. 601,147

2 Claims. (Cl. 226—118)

My invention relates to improvements in bottle filling machines and particularly to that type of filling machine used for filling bottles with carbonated beverages.

One of the objects of my invention is to provide means whereby the level of the water in the filler tank may be varied in accordance with the operator's desires from the exterior of the tank.

In certain types of bottle filling machines the carbonated water to be supplied to the bottles is delivered to a filling tank, from which it passes through the filling valves to the bottles to be filled. The supply of this water is automatically controlled by the liquid level in the tank, through the medium of a float controlled valve. The flow of liquid through the filling valve, that is the rate of flow, and to a certain extent the quantity may be determined by the liquid level in the filling tank, or by the head of the water and by regulating this liquid level, or head, the liquid flow to the bottle may be so controlled as to permit the liquid to flow into the bottle at the most satisfactory rate to fill the bottle and at the same time prevent foaming of the liquid in the bottle due to too rapid passage of the liquid thereto.

It is desirable, of course, to provide means whereby this liquid level may be varied from the exterior of the filler tank.

It is one of the objects of the present invention to provide a filling machine with an improved form of means for controlling the liquid level in the tank which means is operable from the exterior of the tank.

For the purpose of disclosing my invention I have illustrated one embodiment thereof in the accompanying drawing, in which:

Fig. 1 is a partial sectional view of so much of a bottle filling machine as is necessary to disclose my present invention;

Fig. 2 is a detailed sectional view showing the means for controlling the flow of liquid into the tank and means for adjusting the float level of the valve controlling float.

In the embodiment of the invention illustrated, I have shown a bottle filling machine having the usual liquid tank 1 provided with the filling valve 2 adapted to be operated by the raising of the bottle in contact with the filling valve as the filling valves, together with the other parts of the machine, rotate. A liquid is supplied to the tank through a supply pipe 3 connected with a suitable source of carbonated water as for instance a carbonator 4, and the control of the passage of liquid into the tank 1 is controlled by the counter-balancing pressure within the tank. This pressure is

admitted from the top of the carbonator 4 through a controlling valve 5 into the tank. The valve 5 is automatically operated by a float 6 located within the tank.

The filler valve 5 comprises a housing 7 provided with a base portion 8 upon which is disposed a central body portion 9 having a cover member 10. A relatively large diaphragm 11 is disposed between the base portion 8 and the body portion 9, being held in position by suitable bolts (not shown) clamping the two parts together. A relatively small diaphragm 12 is disposed between the body portion 9 and the cover 10, being clamped between these parts, which in turn are clamped together by suitable bolts or screws.

A yoke member 13 extends between the two diaphragms, having a boss 14 at its top on which is adapted to be screwed a clamping nut 15 engaging a clamping plate 16 above the diaphragm 12. A similar boss 17 extends through the diaphragm 11 and has secured thereon a fastening nut 18 which maintains in position a clamping plate 19 for the bottom diaphragm. A guide pin 20 extends upwardly from the boss 14 through the casing or cover, and the cover 10 is provided with one or more openings 21 to permit atmospheric pressure into the chamber formed between the diaphragm and the top cover 10.

A pressure inlet member or nipple 22 extends into the casing 9 or into the body portion 9 and has connected thereto the gas supply pipe 23, which in turn is connected to the top of the carbonator 4. An outwardly opening check valve 24 controls the delivery opening of the port 25 extending through the nipple 22 and this valve is controlled by the diaphragm 11, being adapted to be contacted by a projection 26 of the yoke 13.

This port 25 delivers into a chamber formed between the diaphragms 11 and 12, which chamber communicates by means of a delivery opening 27 with a stem 28, the lower end of which communicates with the top of the filling tank 1. The chamber 29 formed beneath the diaphragm 11 communicates with the port or delivery opening 27 through an opening 30, which opening is controlled by a valve 31 mounted on the top of the stem 32 of the float 6. This stem 32 extends through the hollow stem 28 and as the delivery opening 27 communicates through the stem 28 with the top of the filler tank, it is obvious that the chamber 29 beneath the diaphragm 11 also communicates with the top of the filler tank. This chamber 29 also communicates with the atmosphere through a snifter opening 33, the size of which is controlled by the adjustable valve 34.

The neck or stem 28 extends through the top of the filler tank 1, which tank has extending upwardly therefrom a surrounding hollow stem 35 adapted to receive a packing gland 36. The lower end of this neck or stem 28 is provided with a threaded sleeve 37, clamped in position between a shoulder 38 on the stem 28 and a clamping nut 39 on the lower end of the stem 28. This sleeve is provided with a tongue 37' operating in a slot 37" in the stem 35 to prevent the sleeve from rotating. The sleeve 37 threads through a rotatable nut 40 supported between a spider 41 and the underside of the casing of the tank, which nut on its outer periphery is provided with a beveled gear 42 adapted to mesh with a beveled gear 43 on the end of a rotatable spindle 44 extending through the casing of the filling tank 1 and provided with a rotating hand wheel 45. By this arrangement the height of the float 6 may be adjusted from the exterior of the filler tank, as it will be obvious that by rotating the hand wheel 45, the nut 40 will be rotated thereby, causing a relative movement between the nut and the sleeve 37, thus raising or lowering the entire stem 28 and with it the float 6.

In operation it is to be assumed that the gas pressure in the tank above the liquid level is equivalent to the water supply pressure. We will also assume that the tank is filled to the desired liquid level. Under these circumstances when the water flows out through the bottle filler valve, the water level is reduced thereby permitting the float 6 to descend. This opens the valve 31 establishing communication between the top of the filler tank thereby admitting gas from the filler tank to the chamber 29 from wherein it leaks or bleeds to the atmosphere through the port 33. Pressure from the tank exists in the space between the diaphragms 11 and 12 and this pressure acting on the diaphragm 12, together with the pressure in the chamber 29, although reduced, raises the yoke 13 closing the valve 24 to prevent additional pressure from the carbonator entering the tank. The reduction of the pressure in the tank, due to the bleeding of the valve 33, as well as the lowering of the water level by the drawing off of the water reduces the pressure of the gas above the water in the tank 1 to a point where it is lower than the water supply pressure, thereby permitting water to flow into the tank through the supply pipe 3. The water continues to flow into the tank until the float 6 has raised sufficiently to close the port 30, thus preventing further escape of gas from the tank and into the chamber 29. This chamber, however, being opened through the port 33 to atmosphere permits the escape of the gas in the chamber until the pressure in the chamber is below the pressure of the gas between the diaphragms 11 and 12 so that the pressure on the

underside of the diaphragm 11 is lower than the pressure on the upper side of the diaphragm 11 and with the pressure on the upper side of the diaphragm 11 predominating the diaphragm will be deflected downwardly permitting the valve 24 to open, admitting gas under pressure from the carbonator until the pressure in the tank above the liquid is equivalent to the liquid supply pressure, thus stopping the flow of liquid into the tank. 10

It is obvious that by varying the height of the float in the tank the height of the liquid level may be varied to any degree desired. And in order to vary this height from the exterior of the tank 1 it is merely necessary to rotate the hand wheel 45 in the direction whereby the entire valve mechanism, including the float will be raised or lowered to the desired point. The connecting pipe 23 extending from the carbonator has sufficient flexibility to permit this adjustment without disturbing the connections. The rate of flow from the tank through the bottle filling valve is determined by the head pressure of the water and by adjusting the level of the float to thereby adjust the liquid level in the tank. Thin head flow may be so adjusted as to cause the flow of water into the bottle to coincide with the movement of the bottle during the filling operation so that, the bottle will be filled at the exact point in its movement at about the time it is to be withdrawn from the filler valve and this return of flow may be so determined as to admit the liquid to the bottle at such a rate as to prevent foaming in the bottle. 20 30 35

I claim the following:

1. In a bottle filling mechanism, the combination with a filling tank, of a valve for controlling the admission of pressure to said tank to control the admission of fluid thereto, including a hollow stem member extending through and into said tank, a float within said tank operatively and mechanically connected to said valve, a nut mounted against vertical movement on said tank and engaging a threaded portion of said stem member and means, for rotating said nut to vertically adjust said valve and float. 40 45

2. In a bottle filling mechanism, the combination with a filling tank, of a valve for controlling the admission of pressure to said tank to control the admission of fluid thereto, including a hollow stem member extending through and into said tank, a float within said tank operatively and mechanically connected to said valve, a nut within said tank mounted against vertical movement relative to the tank and engaging a threaded portion on said stem member and means extending to the exterior of said tank for rotating said nut to vertically adjust said valve and float. 50 55 60
